(57) **CLAIM**

The ornamental design for a hook with clip, as shown, and described.

DESCRIPTION

FIG. 1 is a perspective view of a hook with clip;
FIG. 2 is a left elevation view thereof, the right elevation
view being a mirror image thereof;
FIG. 3 is a front view thereof;
FIG. 4 is a rear view thereof;
FIG. 5 is a top plan view thereof; and,
FIG. 6 is a bottom plan view thereof.
The broken lines represent unclaimed matter and form no
part of the claimed design.

1 Claim, 6 Drawing Sheets
